UNITED STATES PATENT OFFICE.

CLARENCE H. WEISE AND FRANK A. McAUVIE, OF ARCHBALD, PENNSYLVANIA;
SAID McAUVIE ASSIGNOR TO SAID WEISE.

MOVING-PICTURE MACHINE.

1,092,549.

Specification of Letters Patent. Patented Apr. 7, 1914.

Application filed May 25, 1911. Serial No. 629,435.

To all whom it may concern:

Be it known that we, CLARENCE H. WEISE and FRANK A. McAUVIE, citizens of the United States, residing at Archbald, in the county of Lackawanna, State of Pennsylvania, have invented certain new and useful Improvements in Moving-Picture Machines; and we do hereby declare the following to be a full, clear, and exact description of the invention, such as will enable others skilled in the art to which it appertains to make and use the same.

Our invention relates to new and useful improvements in moving picture machines, and more especially to the method of handling the film, and the object of our invention is to do away with the rewinding of the film after each showing thereof before it can again be shown, as is now the practice.

A further object of our invention is to provide a means by which a film when wound in the customary manner after having been passed through the machine may be unwound from the center of the reel. By this means the film may again be displayed with the pictures in correct order without the necessity of first rewinding the reel.

With these and other objects in view, our invention will be more fully described, illustrated in the drawings which show a preferred embodiment of our device and then specifically pointed out in the claims which are attached to and form a part of this application.

In the accompanying drawings, Figure 1 is a top plan view of the reel casing from which the film is fed to the machine, the outer cover thereof being swung back to better show the same. Fig. 2 is a vertical section on the line 3—3 of Fig. 1 showing the construction of the reel from which the film is unwound.

Referring more specifically to the drawings, in which similar reference numerals designate corresponding parts throughout, 1 represents in general the casing of the reel from which the film is unwound as it passes to the machine. The casing as shown is preferably constructed of sheet metal, circular in shape, and provided with a hinged

cover 2 the specific construction of which will be hereinafter described. Secured to the central portion of the bottom of this casing is a downwardly extending member 3, 55 preferably cast in a single piece and provided with a cylindrical spherical bore 4 the upper end of which registers with an aperture formed in the bottom of the casing, while the lower end terminates in a conical 60 point 5. As a support for this casing we provide a plate 6 adapted to be secured to the frame of the machine by set screws 7 which engage in slots 8 formed in the plate, whereby the plate is adapted to be adjusted 65 longitudinally while at the same time prevented from vertical movement. Secured to this plate by a set screw 9 is an L-shaped plate 10, which by means of its slot 11 is adapted to be adjusted vertically with respect to the plate 6, and secured to the horizontal portion of the plate 10 and adjustable thereon is a plate 12 the free end of which terminates in a collar 13 through which the member 3 is adapted to extend and be secured by means of the set screws 14. By this means the casing 1 is securely mounted in the frame while at the same time by means of the various adjustments above described, it may be moved to any desired position thereon.

The reel from which the film is unwound, and which is shown in position in Fig. 2 of the drawings, consists of a base member 15 circular in shape, somewhat less in diameter 85 than the internal diameter of the casing in which it is supported and provided at its peripheral edge with an upwardly extending annular flange 16. A spindle 17 the upper portion of which is threaded as shown 90 at 18, is threaded into an aperture formed in the central portion of the base 15 and the lower portion of this spindle is adapted to be seated in the bore 4 of the member 3, whereby the reel is rotatably mounted in the 95 casing and spaced therefrom. Surrounding the upper portion of the spindle is a spool 19 which is secured in place by means of the nut 20 which is threaded upon the spindle and seated in the recess formed in the upper end of the spool, the spindle being so proportioned as to terminate flush with the

upper face of the spool, the reason for which will be later apparent. As shown the upper end of the spool is provided with an annular flange 21 the peripheral edge of which is beveled as at 22 for a purpose which will be hereinafter explained.

Extending outwardly from the side of the casing 1 is an auxiliary casing 23 open at the top and bottom, and hinged thereto is a second or outer cover 24 adapted to close upon the cover 2 and to cover the auxiliary casing and a portion of the main casing. A shaft 25 has its ends secured in the sides of the auxiliary casing and rotatably mounted thereon is a roller 26. A second roller 27 is mounted upon a second shaft 28, the ends of which engage with the diagonally-extending slots 29 formed in the walls of the auxiliary casing in such a manner that the roller 27 normally rests against the roller 26 and if moved out of position will immediately fall back into engagement by force of gravity.

Journalized in suitable bearings 30 carried by the upper face of the main cover 2 is a shaft 31 upon which is rotatably mounted a tapered roller 32. A cylindrical roller 33 is rotatably mounted upon a shaft 34 which is journalized in suitable bearings 35 carried by the cover 2 adjacent the hinge thereof. As shown all of these rollers 26, 27, 32 and 33 are in alinement with each other and are adapted to support and guide the film on its way to the machine, as will be hereinafter described.

Formed in the cover 2 and adjacent the roller 32 is an aperture 36, substantially rectangular in shape and extending to a point adjacent the central portion of the cover, from which it is extended along one side as shown at 37 to form a semi-circular tongue member 38 positioned directly above the spool 19 when the cover is closed, this tongue serving to properly guide the film as it leaves the reel on its way to the rollers, in a manner which will be fully described in the operation of the device.

In machines of the ordinary construction it would now be necessary to rewind the film before again using the same in order to display the pictures in correct order. With our device however this is not necessary as the previously wound film is removed from the winding reel and placed upon the spool 19 of the reel from which the film is to be unwound. When in this position the inner end of the film, or that at the center of the reel is pulled out or drawn upward through the aperture 37 in the top of the casing, and as the film is thus drawn off of the spool it bears against the tapered or cone like flange 21. This tapered flange extends preferably approximately one-third the length of the spool so that the film has an opportunity to

bend in the middle should it become too tight and bind as it pulls off around the cone or tapered flange. It is well understood by those familiar with moving picture machines that the life of the film depends on the length of time it can be plainly displayed. Consequently it is desired to avoid as far as possible bringing the film into contact with parts of the machine which would be liable to blur or destroy the pictures. For this reason we form the bevel on the cone or spool in the manner described so that but very little surface may be brought into contact with the film. With our machine every part which is contacted with by the film moves with such film, so that the friction or wearing of the parts against the film is greatly reduced, and consequently the life of the latter lengthened.

The tongue 38, it will be noted, lies or extends directly above the bevel or cone flange of the spool and acts as a guide for the film as it leaves the casing or magazine, in the sense that this tongue prevents the center of the film from running out spirally as it would do were the tongue not present. As the film is drawn off from the cone-like flange of the spool and beneath the tongue 38 it is led over the rollers 32 and 33 and downwardly between the rollers 26 and 27 and thus to the machine in the customary manner.

As will be readily understood the tapered roller 32 serves to counter-act the tendency toward lateral movement upon the part of the film caused by the twisting of the same as it leaves the reel. When the film has been adjusted as above described, the auxiliary cover 23 is closed upon the reel casing, occupying the position shown in Fig. 2 of the drawings, thus effectually protecting the reel as it is drawn from the casing.

Although we have illustrated and described a specific form of reel construction for carrying out the purpose it will be understood that we in no way limit ourselves to the specific structure disclosed, but retain the right to accomplish our object by means of any suitable form of reel.

What we claim is:

1. The combination with a casing, of a reel rotatably mounted therein and adapted to receive a film, said reel comprising a base having a flange extending therefrom, a spool carried by the base and provided with a beveled flange, a cover for the casing having an opening therein for the passage of the film, a supporting and guide roller journalized in the cover.

2. The combination with a casing, of a rotatable film receiving reel mounted therein, a spool disposed centrally of said reel and provided at its upper end with a beveled

flange, a tongue formed in the cover of the
casing above the spool and having a slot
formed adjacent thereto, a tapered roller
journaled at said slot and over which the
5 film passes from the spool, and guide rollers
for guiding the film when it leaves the
tapered roller.

In testimony whereof, we affix our signatures,
in presence of two witnesses.

CLARENCE H. WEISE.

FRANK A. McAUVIE.
